[57] CLAIM

The ornamental design for a light switch extension
handle, as shown and described.

DESCRIPTION

FIG. 1 is an inverted front elevational view of a light
switch extension handle showing my new design;
FIG. 2 is a rear elevational view thereof;
FIG. 3 is an enlarged top plan view thereof;
FIG. 4 is an enlarged bottom plan view;
FIG. 5 is an inverted side elevational view thereof; and
FIG. 6 is an inverted side elevational view of the side
opposite that shown in FIG. 5.

FIG. 1

FIG. 2

FIG. 3

FIG. 4

FIG. 5

FIG. 6
